UNITED STATES PATENT OFFICE

HUGH S. BRADY, OF WHEELING, WEST VIRGINIA, ASSIGNOR TO HAZEL-ATLAS GLASS CO., OF WHEELING, WEST VIRGINIA, A CORPORATION OF WEST VIRGINIA

CLOSURE FOR RECEPTACLES

Application filed September 30, 1927. Serial No. 222,990.

The present invention relates to closures for bottles, jars and similar receptacles and has special reference to the sealing of such receptacles after they have been vacuumized; 5 although in its broader aspect the invention is also adapted to the closing and sealing of receptacles irrespective of whether or not they have been previously vacuumized.

One of the objects of the invention resides 10 in combining with a closure of the general type shown in my Patent No. 1,544,553, a composition gasket or seal for the top of the container being sealed.

A further object of the invention consists 15 in combining with such a closure a plastic seal for both the top and inner side of the mouth of the container to be sealed.

Another object of the invention resides in 20 so constructing the closure that it will serve as a means to retain the sealing ring in position thereon.

A still further object of the invention is 25 the formation of a cap or closure which will so confine the sealing material as to prevent its escape when pressure, either atmospheric or otherwise, is applied to the closure, and which will also present a neat and attractive package in that it will effectually conceal the sealing material without overlapping the 30 side walls of the receptacle.

Other objects and advantages of the invention will be apparent from the following description when taken in connection with the accompanying drawing; in which

35 Figure 1 is a fragmentary side elevation of a jar having combined therewith the improved closure and seal.

Figure 2 is a plan view of the cap or closure.

Figure 3 is a vertical section through the 40 top of a jar and closure, the same being shown in conjunction with a top and side seal; and

Figure 4 is a section through a cap showing a top seal only, the receptacle being indicated by dotted lines.

Referring to the drawing in more detail, the numeral 1 indicates a jar or the like, preferably made of glass or similar material, and the closure which is preferably of flexible 50 metal, is indicated generally by the numeral

2. This closure while intended more particularly for use in the vacuum sealing of receptacles is also well adapted to use in the sealing of receptacles without exhausting the air therefrom.

The closure 2 is provided with a dome-shaped central portion 3 from the edge of which rises an outwardly inclined wall 4 terminating in a horizontal flange 5.

In the form of the invention shown in Figure 3 a sealing ring 6 of plastic composition material is provided and is disposed on the under side of the flange 5 and the outer side of the wall 4. This ring is retained in position partly by means of a bead or projection 7 which is bent down from the outer edge of the flange 5 so as to encompass the outer edge of the sealing ring and to engage over a portion of its under surface. Such a construction serves a three-fold purpose, namely, to assist in retaining the sealing ring in its proper position on the closure, to prevent the lateral escape of the plastic material of which the ring is formed when pressure is applied in sealing the receptacle, and to present 70 a neat and attractive package by concealing the plastic material from view.

The horizontal portion of the ring 6 is, of course, adapted to seat upon the upper edge of the receptacle to be sealed and the downwardly extending portion which is in engagement with the inclined wall 4 is adapted to be compressed against the inner wall of the mouth of the receptacle by reason of the outward expansion of this wall as the dome 3 is 80 more or less collapsed by atmospheric pressure. This action of the dome 3 in compressing the sealing material against the inner wall of the receptacle is quite similar to the action described in my patent heretofore 85 referred to in which a rubber gasket is employed as the sealing medium, and a detailed description of this operation is believed to be unnecessary.

In the form of the invention shown in Figure 4 the plastic sealing ring 8 is identical with the ring 6 except that the vertical portion thereof is omitted so that the gasket serves as a top seal only. The bead 7 performs the several functions heretofore de- 100

scribed in connection with the disclosure of Figure 3, i. e., it retains the sealing material in position on the under side of the flange 5, prevents the lateral escape of the material as pressure is applied to the closure, and serves to conceal the sealing material in the finished package.

In the operation of both forms of the invention, the sealing material is applied to the closure as indicated in Figures 3 and 4 and is retained in position thereon partly by means of the bead or crimped portion 7. The closure, with either type of gasket, is placed upon the receptacle to be sealed, and the receptacle is then vacuumized and the closure forced into position; any desired form of vacuumizer or sealer being employed for this sealing operation. In the form shown in Figure 3, atmospheric pressure on the dome 3 will force the wall 4 outwardly, thereby assisting in the maintenance of an effective seal. As pressure is applied to the closure the flange 5 will, of course, force the horizontal portion of the gasket, in either form of the invention, into sealing contact with the upper edge of the receptacle, and any tendency of the sealing material to escape from under the flange 5 is prevented by means of the bead 7 which acts as a barrier to such a movement.

From the foregoing description taken in connection with the accompanying drawing the utility and efficiency of the embodiments of the invention shown herein will be apparent, and it will also be observed that the bead 7 which retains the sealing material in position on the closure not only insures against the escape of this material from the point of sealing contact but also greatly enhances the appearance of the completed package, due to the fact that the sealing material is concealed without the necessity of extending the closure down along the sides of the receptacle and thus breaking the continuity thereof.

While I have described what I now believe to be the preferred embodiments of the invention it is to be understood that various changes may be made in the details of construction without departing from the essentials of the invention; and all such changes and modifications are intended to be included within the scope of the appended claims.

Having fully described my invention, what I claim as new and desire to secure by Letters Patent is:

1. The combination with a glass receptacle of a cover therefor, said cover including a substantially vertical wall disposed within the mouth of the receptacle adjacent its inner wall, a horizontal flange, a composition sealing ring of plastic material disposed between the flange and the mouth of the receptacle, and means on the outer edge of the flange 60 to prevent the escape of the sealing material.

2. The combination with a glass receptacle of a cover therefor, said cover including a substantially vertical wall disposed within the mouth of the receptacle adjacent its inner wall, a horizontal flange, a composition sealing ring of plastic material disposed between the flange and the mouth of the receptacle, and a flange on the outer edge of said first-mentioned flange to prevent the escape of the sealing material.

3. The combination with a glass receptacle, of a cover therefor, said cover including a central portion, an upwardly inclined wall about the periphery of said central portion and disposed adjacent the inner wall of the mouth of the receptacle, a flange extending laterally from the upper edge of the inclined wall, a sealing ring of plastic material disposed beneath said flange, and a downturned annular projection on the outer edge of said flange for engaging said ring.

4. The combination with a glass receptacle, of a cover therefor, said cover including a central portion, an upwardly inclined wall about the periphery of said central portion and disposed adjacent the inner wall of the mouth of the receptacle, a flange extending laterally from the upper edge of the inclined wall, a sealing ring of plastic material disposed beneath said flange, and a downwardly and inwardly turned annular projection for engaging the outer edge of said ring.

HUGH S. BRADY.
